CLAIM

The ornamental design for a display device, as shown and described.

DESCRIPTION

FIG. 1 is a front right perspective view of the display device; FIG. 2 is a rear perspective view of the display device of FIG. 1;

FIG. 3 is a front elevation view of the display device of FIG. 1;

FIG. 4 is a rear elevation view of the display device of FIG. 1;

FIG. 5 is a top plan view of the display device of FIG. 1; FIG. 6 is a bottom plan view of the display device of FIG. 1;

FIG. 7 is a right side view of the display device of FIG. 1; and,

FIG. 8 is a left side view of the display device of FIG. 1; The broken line showing of the face and back surfaces is included for the purpose of illustrating only and forms no part of the claimed design.
